UNITED STATES PATENT OFFICE.

WILLIAM E. SPARKS, OF NEW HAVEN, CONNECTICUT, ASSIGNOR TO SARGENT & CO., OF SAME PLACE.

DESIGN FOR CHEST-HANDLE.

Specification of Design No. 5,346, dated October 31, 1871.

To all whom it may concern:

Be it known that I, WILLIAM E. SPARKS, of New Haven, in the county of New Haven and State of Connecticut, have invented a new Design for Chest-Handle; and I do hereby declare the following, when taken in connection with the accompanying drawing and the letters of reference marked thereon, to be a full, clear, and exact description of the same, and which said drawing constitutes part of this specification and represents a perspective view.

This invention relates to a design for chest-handle; and consists in the configuration of the parts as shown in the accompanying illustration and as hereinafter described.

The base or plate A is flat, the surface pan-

eled, with a plain edge, and from this base the barrel B rises, contracting to a flat surface, and the surface paneled. Into the ends of the barrel the trunnions or ends of the handle C are hung, the surface of the said handle paneled, the whole as shown in the illustration.

As the base may be used with a different handle, and vice versa, I do not confine my design to the combined handle and base; but

I do claim—

The design for chest-handle and base, as shown and described, separately or together.

WILLIAM E. SPARKS.

Witnesses:

A. J. TIBBITS,
J. H. SHUMWAY.
